UNITED STATES PATENT OFFICE.

ALBERT E. MAYNARD, OF SOUTHERIDGE, MASSACHUSETTS, ASSIGNOR TO AMERICAN OPTICAL COMPANY, OF SOUTHERIDGE, MASSACHUSETTS, A VOLUNTARY ASSOCIATION OF MASSACHUSETTS.

TOOL HOLDER FOR GRINDING MACHINES.

Application filed July 8, 1919. Serial No. 309,356.

To all whom it may concern:

Be it known that I, ALBERT E. MAYNARD, a citizen of the United States, residing at Southbridge, in the county of Worcester and State of Massachusetts, have invented 5 certain new and useful Improvements in Tool Holders for Grinding Machines, of which the following is a specification.

This invention relates to new and useful 10 improvements in lens grinding machines and more particularly to what will be hereinafter termed an adapter which is to be universally used on various types of lens grinding machines whereby all types of 15 lenses can be readily ground upon the same machine.

Another object of the present invention 20 is the provision of an adapter which can be applied to any well known form of lens grinding machine and is provided with means whereby different types of tools can 25 be readily interchanged upon the holder so that either spherical, concave, convex, or other various types of lenses can be readily 30 ground on the same machine.

A further object of the invention is the 35 provision of an adapter of the above type provided with novel means for attaching and detaching the various tools in connection 40 with the holder so that the different types of tools used in connection with the holder can be readily changed as desired.

With the above and other objects in view 45 the invention consists in the combination and arrangement of parts hereinafter more fully set forth, pointed out in the claims, and shown in the accompanying drawings, in which—

Figure I is an elevation of an adapter 50 constructed in accordance with my invention.

Figure II is a transverse sectional view of the same.

Figure III is a top plan view.

Figure IV is a longitudinal sectional view 55 taken through one of the detachable holders.

Figure V is a side elevation of one of the laps adapted to be fitted in connection with the holder illustrated in Figure IV.

Figure VI is a side elevation of another 60 form of holder, parts thereof being broken away and in section.

Figure VII is a detailed cross section illustrating the form of lap that will be used

in connection with the holder illustrated in 55 Figure VI.

Figure VIII is a longitudinal sectional view taken through another modified form of holder.

Figure IX is a side elevation of another 60 form of lap adapted to be used in connection with the holder illustrated in Figure VIII.

Figure X is a top plan view of another 65 form of lap which can be used in connection with the holder illustrated in Figure VI.

Figure XI is a transverse sectional view of the lap illustrated in Figure X.

Figure XII is a transverse sectional view 70 taken as on the line XII—XII of Figure III.

Referring now more particularly to the 75 drawings, in which the various reference characters indicate the several parts throughout the views, the numeral 1 designates the main holder of my improved adapter, which in the illustration is shown of a conical shape type and is provided at its central portion with an enlargement 2 having a central threaded opening 3 whereby 80 the adapter may be readily attached to the lens grinding machine. It will be understood that in the construction of this adapter it is the object of applicant to provide an adapter which may be readily fitted 85 to various well known commercial grinding machines. This central portion 2 is further provided with the spaced openings 4 which extend upwardly therethrough.

Extending transversely through the body 90 of the adapter is a shaft 5 upon each end of which is mounted a bearing member 6 securely held in place and at the same time adapted for adjustment by means of the set screws 7. These bearing members 6 are provided upon the outer face thereof with spaced ears 8 between which are fitted the lower ends of the spaced guard arms 9, said arms being held securely in place by means of the screw bolts 10 which are fitted into 100 the bearings 6 between the arms 9 and are adapted to bear against the arms 9 to securely retain them between the spaced ears 8.

The various tools which are used in connection with my improved adapter and 105 which go to form a complete adapter, are constructed in various shapes and in accordance with the various type of lenses to

be ground. In Figure IV, I have illustrated in sectional view a particular type of holder which includes a circular body portion 10 having a central opening 11 and further provided at one end with the spaced openings 12. From a view of the drawings it will be noted that the openings 12 are screw-threaded, whereby the tool 10 may be readily secured to the holder 1 after having been placed in position upon the upper face of the enlarged portion 2, it being understood that the screws 13 will be inserted up through the openings 4 and engaged with the threaded openings 12. In placing the tool holder 10 in position upon the adapter the pins 14, which are arranged in opposed relation with the openings 4, are adapted to fit within the openings 15 in the tool holder 10 so as to retain it in its proper centered position with respect to the adapter until the screw members 13 can be engaged within the openings of the tool holder 10. From this it will be apparent that the parts are securely held against any rotating movement during the grinding operation. As illustrated in Figure IV, this tool holder 10 is provided with a central opening, the upper end of which is divided from the lower end by means of a circular rib 16, the upper end of said opening being adapted to receive the shank portion 17 of the lap 18, said lap being illustrated in the present drawings as of the concave type adapted to be used particularly for grinding concave lenses.

In Figure VI, I have illustrated another form of tool holder which consists of an annular body member 19 having the spaced screw openings 20 arranged at diametrically opposite points on the lower face of the body and adapted to correspond with the openings 4 in the holder. This tool holder is also provided with the spaced openings 21 adapted to receive the pins 14 when being placed in position upon the holder so as to actively center and retain the holder in position until the screws can be engaged with the openings 20. This holder is provided with an upstanding tapering shank 22 upon which is mounted the lower extending sleeve portion 23 of the lap 24 which in the present instance is illustrated as particularly adapted for grinding spherical lenses.

In Figure VIII, I have illustrated still another modified form which consists of an annular body member 25 provided within its upper portion with a substantially rectangular opening 26 which extends in through the body midway of its length and is adapted to receive a substantially rectangular portion 27 of the lap 28. This lap 28 is securely held in position by having the set screw 29 threaded through the wall of the holder 25 and engaged with the shank 27 of the lap whereby the lap may be re-

moved when desired to be replaced by a new one or one of a different size from the one heretofore placed in position in the holder. This holder 25, as illustrated in Figure VIII, is provided with the usual screw openings 30 in the end thereof opposite the opening 26 and also provided with the pin-receiving openings 31 whereby this holder may be quickly placed in position upon the main holder 1 and securely held against movement.

In Figures X and XI I have illustrated still another modified form which consists of a sleeve 32 herein shown as adapted to be fitted over the shank portion 22 of the holder 19, and is provided at its upper end with the substantially elongated body member 33 having a flat upper face 34 provided at one end with a stationary upstanding flange 35. It will be noted from the illustration and the drawings that a lens is retained in position upon the upper face of the body member 33 by means of a detachable plate 36 which is removably secured to the end of the body opposite the flange 35 by means of a screw member 37 which extends through the plate 36 and is threaded into the end of the body member 33. In order to provide against turning movement of the plate 36, the pins 38 are provided, one end of which engages in suitable openings in the plate 36, while the other ends engage in suitable openings in the end of the body 35. Thus, when the plate 36 is tightened against the lens upon the body member 33, the pins 38 will prevent any turning movement of the plate 36, thus securely holding the lens in position upon the body.

While I have shown and described only a few of the various forms of tools adapted to be used in connection with my improved holder, it will be apparent that a great number of different types of lap holders may be used in connection with the main holder, and various types of laps can be used in connection with the different holders herein illustrated and described. As stated heretofore, it is the main object of my invention to provide an improved adapter for lens grinding machines whereby the different types of laps and tool holders can be readily interchanged so that all types of lenses can be readily ground upon the same machine.

I claim:

1. A tool holder for grinding machines comprising a base member having opposed sockets, one of said sockets having guide members projecting outwardly therefrom, and a tool engaging stud fitting within said socket of the base member having sockets formed therein to receive the guides, said stud and base member having aligned apertures formed therein and fastening members passing through the base member and into

the stud to detachably connect said parts.

2. In a device of the character described, the combination with a base member having a socket formed in the upper face thereof, of a tool receiving stud adapted to rest on the bottom of the socket and be held against lateral displacement by the side walls of the socket, the body portion at the bottom of the socket being pierced and the 10 stud having threaded sockets adapted to align with the pierced portions of the base member, and fastening devices passing through

the pierced apertures in the base member for engagement in the sockets of the stud to draw the stud into tight engagement with 15 the bottom of the socket, substantially as illustrated.

In testimony whereof I have affixed my signature, in presence of two witnesses.

ALBERT E. MAYNARD.

Witnesses:

H. E. COLEMAN,
ALICE G. HASKELL.
